UNITED STATES PATENT OFFICE.

LOUIS C. LOEWENSTEIN, OF LYNN, MASSACHUSETTS, ASSIGNOR TO GENERAL ELECTRIC COMPANY, A CORPORATION OF NEW YORK,
ELASTIC-FLUID TURBINE.

1,242,005.

Specification of Letters Patent.

Patented Oct. 2, 1917.

Application filed March 4, 1915. Serial No. 12,058.

To all whom it may concern:

Be it known that I, LOUIS C. LOEWENSTEIN, a citizen of the United States, residing at Lynn, in the county of Essex, in the 5 State of Massachusetts, have invented certain new and useful Improvements in Elastic-Fluid Turbines, of which the following is a specification.

The present invention relates to steam 10 turbines and particularly to the operating and governing of small units.

The primary object of the invention is to provide an arrangement for controlling or governing a steam turbine which is extremely simple, requires little care or attention on the part of the attendant, and which will effectually obviate any possibility of the turbine running away.

A further object is to provide a turbine 20 having two distinct nozzles or sets of nozzles, through either of which the turbine may be operated so that in case one nozzle or set of nozzles should become clogged or inoperative the other can be used.

In carrying out my invention I provide 25 a steam turbine comprising a suitable casing having a rotor therein and provided with two independent nozzles or sets of nozzles. The pipe line or conduit which conveys motive fluid to the turbine is provided with a branch leading to each nozzle or set of nozzles, and a suitable valve arrangement is provided whereby motive fluid may be directed to either branch.

For regulating the turbine I dispense with the usual (and more troublesome and expensive) speed governor and emergency shut-off means commonly considered necessary, and control the turbine primarily by means 40 of a reducing valve located in the pipe or conduit which conveys the elastic fluid to the turbine nozzle or nozzles. The turbine nozzle or nozzles are designed with a properly determined area so that with a certain 45 steam pressure supplied, the turbine will run at the desired speed. The reducing valve will be set to reduce the existing steam pressure exactly or approximately to a desired value, and will be fixed and left in this position. The turbine will then be 50 started and stopped by means of a suitable shut-off valve. In connection with the use of a reducing valve it may happen that due

to slugs of water or dirt, or trouble with the mechanism itself, the reducing valve would 55 stick open or fail to function properly, and in order to safeguard the turbine in such a case I provide in the steam line between the reducing valve and the turbine a pop-safety valve of suitable structure. It will be ad- 60 justed so as to keep the pressure below a certain predetermined maximum above that called for by the reducing valve.

It might furthermore happen that, in the event of the reducing valve sticking open, 65 that the safety valve would not lift quickly enough or sufficiently enough to relieve the pressure in the elastic fluid line leading to the turbine, and thus the turbine might be caused to race. This is particularly true 70 when the motive fluid supply is from a source of very high pressure. To provide against this possibility, and more particularly to allow the use of a smaller pop-safety valve than ordinarily necessary, I 75 place in the pipe line a member having a comparatively small orifice so as to restrict the area of the pipe line at this point and to prevent in any event a large flow of fluid from the source to the turbine. This member will preferably be located between the source of elastic fluid and the reducing valve, and may with advantage be located adjacent to and structurally combined with 80 a steam strainer or with a steam separator, 85 (if any be used) as will be more fully explained hereinafter. The strainer will preferably be located in advance of the member as regards the direction of flow so as to protect the orifice.

Considered from one point of view, the pop-safety valve and orifice act together in case of a failure of the reducing valve, as the orifice acts to limit the flow of fluid to such an extent that the pop-safety valve can 95 readily take care of the excess over that required by the nozzle or nozzles and limit the pressure to below a certain fixed maximum. On the other hand, should the pop-safety valve too fail to function, the orifice will still act to limit the steam flow to such an extent that the turbine cannot overspeed 100 dangerously.

My invention is primarily intended for use where the turbine unit is small, the load 105 on it is substantially constant, and the effi-

ciency is of secondary importance as compared with simplicity and first cost. One use to which my invention is particularly applicable is in connection with a steam locomotive for driving a fan or blower for inducing forced draft in the stack or for driving the small generator of a headlight set.

For a consideration of what I believe to be novel and my invention attention is directed to the accompanying description and the claims appended thereto.

In the accompanying drawings, Figure 1, illustrates diagrammatically a steam locomotive having a turbine driven electric headlight set with my improvements applied thereto; Fig. 2 is a detailed view of the turbine driven generator showing more clearly my improvements, and Fig. 3, is a detail sectional view on line 3—3, Fig. 2.

Referring to the drawings, 4 indicates a steam locomotive and 5 the steam dome. 6 is a small turbo-generator set for supplying electricity to the headlights 7 and such other lights as may be desired. 8 indicates the turbine casing which houses a suitable turbine rotor, and 9 the exhaust conduit. The turbine is provided with two independent nozzles or sets of nozzles to which are connected the pipes 10 and 11 respectively. These pipes are connected into a three-way valve coupling 12 with which also connects the pipe or conduit 13 which conveys steam from the steam dome 5. By turning the valve the steam from pipe 13 may be directed into either of the pipes 10 or 11.

Arranged in the pipe 13 are the pop-safety valve 14, the reducing valve 15, the combined strainer and orifice member 16 (shown in section in Fig. 3), and the engineer's controlling valve 17. The safety valve 14 and reducing valve 15 may be of any suitable construction, and are illustrated only in a general way. Between the reducing valve and the turbine a suitable pressure gage may be provided as indicated at 18.

Referring to Fig. 3, the pipe 13 is shown as being divided and joined by a usual form of coupling comprising a pair of flanged members 19 and 19^a threaded to the respective pipe ends and suitably joined as by the member 20. The flanged member 19 is counterbored to provide an annular shoulder 21 against which abuts the cup-shaped member 22. This member is provided with a small centrally located orifice 23 and with a flange 24 which fits between the flanges of the members 19 and 19^a. Attached to the flange 24, as by means of the washer 25 and rivets 26, is the strainer 27 formed of suitable material as wire gauze.

In operation, the safety valve and reducing valve having been properly adjusted, the attendant has merely to open and close his valve 17 to start and stop the turbine. No

further attention on his part is necessary. This feature is of great importance in an apparatus of this character, when, for instance, it is applied to a locomotive as it relieves the engineer of all responsibility or care in connection therewith. He has no adjustments to make and no regulating mechanism with moving parts to watch. It does not, therefore, in any way detract him from his regular duties.

The valve 12 will be set to direct the motive fluid to one or the other of the pipes 10, 11, for example pipe 10. Should the nozzle or nozzles with which this pipe connects become clogged while the locomotive is on the road, the engineer or attendant has simply to turn the valve 12 to shut off pipe 10 and direct the motive fluid to pipe 11. This can be done in an instant and avoid the delay which would be necessary to clean out the clogged nozzle as would otherwise be the case.

By the above arrangement a very simple governing arrangement is provided which is practically proof against accident or derangement. Should the reducing valve be improperly set, or fail to function properly for any reason, the pop-safety valve will readily relieve all the steam which can pass through the orifice in the pipe line, or even should the safety valve stick the amount of steam which could pass through the orifice would not be sufficient to raise the pressure to a point where the apparatus would be injured.

By way of illustration, if the normal pressure of steam to be supplied to the turbine is approximately 110 lbs. gage the reducing valve should be set for about 110 lbs. gage and the pop-safety valve may be set at about 115 lbs. gage. Should the reducing valve fail to operate the safety valve will open when the pressure reaches 115 lbs. gage and waste more or less steam to the atmosphere, keeping the pressure of the turbine to substantially its normal value of 110 lbs. gage. Should, however, the pop-safety valve for some reason become impaired or sluggish while the reducing valve is inoperative or stuck open, the orifice will so limit the maximum flow of motive fluid to the turbine that the pressure on the turbine cannot exceed a safe value. Without this orifice the turbine would be subjected to nearly the full pressure of the source.

On a turbine apparatus constructed in accordance with my invention the following measurements were taken, the values given being approximate gage pressures. In each instance the pressure of the source for the turbine was 165 lbs. and the normal operating pressure for the turbine 110 lbs. The orifice had an area slightly larger than that of the steam nozzle of the turbine.

1. With the reducing valve set at 110 lbs. 130

and the pop-safety valve set at 115 lbs. and with an orifice having an area slightly larger than the steam nozzle of the turbine, the pressure after the orifice in the direction of steam flow was 150 lbs.; the pressure beyond the reducing valve was 110 lbs. and the pressure at the nozzle of the steam turbine was 109 lbs.

2. With the reducing valve blocked open 10 so as to be inoperative, the arrangement being otherwise the same as before, the steam pressure beyond the orifice was 115 lbs.; the steam pressure beyond the pop-safety valve which was operating was 111 lbs.; and 15 the pressure at the turbine nozzle was 109 lbs.

3. With the reducing valve blocked open and the pop-safety valve so set as to be inoperative, other conditions again being 20 the same as before, the pressure beyond the orifice was 128 lbs. and the pressure at the nozzle 115 lbs.

4. Without the orifice, and with the reducing valve blocked open and the pop-safety valve so set as to be inoperative, other 25 conditions being the same as heretofore, the pressure at the steam turbine nozzle was 153 lbs.

As already stated, I prefer to arrange the 30 strainer in advance of the orifice, and the orifice in advance of the reducing valve as regards the direction of flow, but it will be understood that other arrangements may be used. For example, the orifice might be 35 located between the reducing valve and pop-safety valve, or even between the pop-safety valve and the turbine, although this last arrangement is not as effective as the others. Furthermore, the strainer and orifice may 40 be separately formed and inserted. It will also be understood that within the scope of my invention certain of the regulating elements may be used without others, although the arrangement that I have illustrated is 45 the one which I now prefer, and the one which I believe to be the most efficient. For example, I may use only the reducing valve for regulating, or I may use the reducing valve in connection with only the pop-safety 50 valve, or I may use other combinations, such as fall within the scope of the appended claims.

In accordance with the provisions of the 55 patent statutes, I have described the principle of operation of my invention, together with the apparatus which I now consider to represent the best embodiment thereof; but I desire to have it understood that the apparatus shown is only illustrative, and 60 that the invention can be carried out by other means.

What I claim as new and desire to secure by Letters Patent of the United States, is:—

1. A locomotive having a boiler which 65 delivers steam at varying pressure and an elec-

tric lamp, in combination with a turbine and generator driven thereby, the turbine receiving its steam from the boiler and the generator supplying current to the lamp, said turbine having an invariable steam admission and said generator having a substantially constant load, a steam conduit connecting the boiler and the turbine, and a pressure reducing valve that regulates the flow of steam from the boiler through the 75 turbine which is set to deliver steam at a pressure below the minimum of that generated by the boiler.

2. The combination of a source of elastic fluid supply, an elastic fluid turbine, a conduit connecting the supply to the turbine, and means in said conduit for controlling and regulating the turbine, said means comprising a reducing valve which is set to reduce the pressure of the supply to the value 80 desired for operating the turbine, a pop-safety valve located between the reducing valve and the turbine adjusted to keep the pressure below a certain maximum above that called for by the reducing valve, a member 85 having an orifice therein which defines a passage of restricted area through the conduit, and a valve which is adapted to be opened and closed to start and stop the turbine.

3. The combination of a source of elastic fluid supply, an elastic fluid turbine, a conduit connecting the supply to the turbine, and means in said conduit for controlling and regulating the turbine, said means comprising a reducing valve which is set to reduce the pressure of the supply to the value 90 desired for operating the turbine, a member having an orifice therein which defines a passage of restricted area through the conduit, and a valve which is adapted to be opened and closed to start and stop the turbine.

4. A locomotive having a boiler which delivers steam at varying pressure and an 110 electric lamp, in combination with a turbine and generator driven thereby, the turbine receiving its steam from the boiler and the generator supplying current to the lamp, said turbine having an invariable steam admission and said generator having a substantially constant load, a steam conduit connecting the boiler and the turbine, a pressure reducing valve that regulates the flow of steam from the boiler through the turbine 115 which is set to deliver steam at a pressure below the minimum of that generated by the boiler, and a pop-safety valve arranged between the reducing valve and the turbine.

5. The combination with a turbine and a 125 conduit for conveying motive fluid thereto, of regulating means for the turbine comprising a reducing valve in said conduit for limiting the flow of motive fluid to the turbine, and a pop-safety valve, and a means 130

defining a passage of restricted area in said pipe for limiting the flow upon failure of the reducing valve to function.

6. The combination with a turbine and a conduit for conveying motive fluid thereto, of regulating means for the turbine arranged in said conduit and comprising a reducing valve, a pop-safety valve located between the reducing valve and the turbine,

and a member having a small orifice located 10 between the reducing valve and the source of fluid supply.

In witness whereof I have hereunto set my hand this 2d day of March, 1915.

LOUIS C. LOEWENSTEIN.
